UNITED STATES PATENT OFFICE.

CORNELL FLAGSTAD, OF MINNEAPOLIS, MINNESOTA, ASSIGNOR OF NINETY-FIVE PER CENT TO FOLDING CRATE AND BOX COMPANY, OF MINNEAPOLIS, MINNESOTA, A CORPORATION OF MINNESOTA.

COLLAPSIBLE CRATE.

Application filed July 5, 1924. Serial No. 724,320.

This invention relates to collapsible and returnable carriers, and the main object is to provide a collapsible crate of a novel, efficient and practical construction, in which the various crate sections are secured together in such a manner that when the crate is emptied and collapsed for return shipment it will be securely contained within a parcel occupying but a comparatively small space of that required for the crate when set up. A further object is to provide a crate of a collapsible nature in which the various parts are arranged in a novel manner whereby the crate cannot only be knocked down and set up in a minimum time, but also which, when set up, will be very rigid and strong, and wherein any normal or excessive strain on the crate will be taken up almost entirely by the main sections thereof directly, thus relieving and preventing any undue strain on the hinges and other more delicate parts. Further and more specific objects will be disclosed in the course of the following specification, reference being had to the accompanying drawings, wherein:

Fig. 1 is an end (or side) elevation of a crate embodying the principles of the invention.

Fig. 2 is an enlarged sectional elevation on the line 2—2 in Fig. 1, a central portion being broken out.

Fig. 3 is a sectional view through the crate, when collapsed.

Fig. 4 is an enlarged detail perspective view of a hinge member used in the crate.

Fig. 5 is an enlarged sectional detail view on the line 5—5 in Fig. 2.

Fig. 6 is an enlarged detail section on the line 6—6 in Fig. 2.

Fig. 7 is a detail plan view on the line 7—7 in Fig. 2.

Fig. 8 is a detail section on the line 8—8 in Fig. 7.

Fig. 9 is an enlarged detail section on the line 9—9 in Fig. 7.

Fig. 10 is a perspective outline showing the folding method.

Fig. 11 is a perspective view showing certain modifications in the crate.

Fig. 12 is a detail section as seen about as on the line 12—12 in Fig. 11.

Fig. 13 is a sectional detail illustrating certain modifications in the crate as shown for instance in Fig. 11.

Fig. 14 is a perspective view of the end 55 of a crate showing further modifications of the structure in Fig. 11, fractional portions being broken away.

Fig. 15 is an enlarged sectional detail view as seen on the line 15—15 in Fig. 14. 60

Fig. 16 is a perspective view of a crate showing further modifications.

Fig. 17 is a side view of the crate, shown in Fig. 16, collapsed.

Fig. 18 is an enlarged detail sectional view 65 on the line 18—18 in Fig. 17.

Fig. 19 is an enlarged fractional section on the line 19—19 in Fig. 16.

Fig. 20 is an end view of a modified form 70 of the crate.

Fig. 21 is an enlarged sectional detail view on the line 21—21 in Fig. 20.

Fig. 22 is a sectional elevation through a crate, having further modified features, looking toward the end of the crate as from the 75 inner side.

Fig. 23 is a side (or end) view of a crate illustrating certain further modifications.

Fig. 24 is an enlarged detail section on the line 24—24 in Fig. 23. 80

Many of the important features of the invention are common to all the crates shown in the drawings. It is found, however, that certain features and details of construction must be altered or modified to meet the needs 85 of various classes of crates as used in the trade. Thus, for instance, a crate used for shipping poultry, as in Figs. 1 to 10, inclusive, and 23 and 24, is of a lower type than those shown in other figures, which may be 90 used for other purposes such as for shipping machinery, furniture, washing machines, ice boxes, engines or other heavy articles, and therefore the relative proportions of the sections which make up the crate will require 95 that slightly different constructions and methods of folding operation be employed.

Referring to the drawings by reference characters, A designates the base or bottom section of a collapsible crate having a cover or top section B, side sections C and D, and end sections E and F. These reference letters with suitable exponents or index numbers, to designate modified forms, will be employed to designate corresponding sections in all of the figures. 100

Attention will for the moment be first and more particularly directed to the crate 105

structure illustrated in Figs. 1 to 10, inclusive. In this crate the base or bottom section A consists of a floor 26 having bottom end cleats 27 and a bias or angled slat 28. 5 One end of the base has a small strip 29, the height of which is equal to the thickness of the horizontal slats 30 of the section D, while the opposite end of the base has a strip 31, which is twice as high as 29, for 10 reasons later to be set forth. The sections C and D are completed by legs or uprights in the form of slats 32, nailed or otherwise suitably secured to the members 30. The section D is hingedly secured to the base A 15 by hinges, each of which consists of a reinforcing strap 33, having a pintle 34 which centers at the upper outer corner of the strip 29 and at the center of the bottom edge of the side section, as shown in Figs. 2 and 20 3, so that the side section cannot swing inwardly and can only swing out to an angle of ninety degrees to the position shown in Fig. 3.

The side section C is hinged to the base A by hinges 37 the pintles of which center at the inner adjacent corners of the members 31 and 32 so that the section C cannot swing outwardly but only inwardly, as in 25 Fig. 3, and so as to leave a space, the thickness of a section, between it and the base, this space being arranged to receive the end sections E and F, as will later be described.

The cover section B consists of a frame 35 of crossed slats 35 and 36, and is permanently secured to the section C by hinges 38, one of which is detailed in Fig. 4, the pintle being arranged so that when the crate is collapsed the sections B and C will lie in the same plane, as shown in Fig. 3. This hinge 38 consists of a U-shaped member 47, clamped over the section C, and a heavy wire bail 48 which is secured to the section B. The member 47 is preferably provided with 40 a punched up tongue 49 which, with the upper part of the member, is nailed down upon the upper end of the section, so that a nail driven through the perforations 50 will 45 strengthen the pintle bearing 51 and prevent it from being opened up or pulled out of shape by the cover section.

A strip 39 is secured on the inner side of the section C to receive and support the ends of the slats 35, and thus relieves the 55 hinges 38 of any strain such, for instance, as would result from heavy baggage or other articles being placed upon the crate. Similarly it will be noticed that such strain from 60 above on the sections C and D will be directly on the base members 29 and 31, thus also relieving the hinges 33 and 37. The other ends of the slats 35 of the cover section B normally rest upon the upper end 65 of the section D, the latter of which is preferably reinforced by a strip 40. The cover

is hingedly and detachably secured to the section D, as at 41, by devices one of which is detailed in Figs. 7, 8 and 9, and may be described as follows: Inset into the end of the slat 35 is a latch member 42 having a slot 43 and a spring held bolt 44, the bolt 44 being retractable by a finger piece 45. A bail member 46, secured to the section D, projects up into the slot 43 for locking engagement over the bolt 44, and its upper end is angled inwardly (Fig. 9) so that it may be engaged either when the sections B and D are at right angles (as in Figs. 7, 8 and 9) or when they are flat against each other, as in Fig. 3.

The end sections E and F consist of end legs or vertical slats 52 and horizontal slats 53. They are hingedly secured directly to the base section, as at 54, and within the vertical limits thereof, as shown in Fig. 5. A filler strip 55 is secured to the base so as to close the space between the legs 52 and to form a rest for the lower edge of the lowest strip 53, when the section is in a vertical position. This strip is of the same height as the section E (or F) is thick. The sections E, F are arranged to engage the inner sides of the sections C, D, to brace them, and are provided with vertically projecting tongues 56 for locking engagement in slots 57 in the cover section, strengthening straps 58 being secured adjacent to the slots to reinforce the adjacent cover section material.

Now when the crate is to be collapsed the latch bolts 44 are first pulled back to release the cover from the section D, which is then either dropped down to a horizontal position or left standing. In a low and long or wide crate the cover may be swung temporarily over and back to rest on the floor, as in Fig. 10, without straining the hinges 38. This releases the tongues 56 of the sections E and F which are then free to be folded into the crate (as indicated in Fig. 10). If the crate is so high that the sections E, F 110 cannot be folded in without overlapping, a slightly different construction, later to be described, is used.

The cover can now be swung forward to its original position and re-attached to the section D, whereupon the sections C, B, and D may be collapsed, through a parallelogram figure, until they are all in a horizontal and parallel position. In this knocked down or collapsed condition it will be obvious that practically all the space defined by the crate is filled with the various sections thereof which are very closely nested together. The crate may also be locked in its collapsed condition as will be described in connection with one of the modified forms. A reverse operation will of course restore the crate to its set up position.

In the crate shown in Figs. 11 and 12 the end sections E¹ and F¹ are detachable so that

they can be removed and placed within the crate, when collapsed, as this crate is too high to permit them being folded down upon the base A¹ without overlapping. In this case the section C¹ is hinged directly to the base as at 59 in such a manner that when folded down the outer members 60, 61 and 62 will fall into horizontal alignment with the floor members 63 of the base. The legs 64, however, are on the inside of the hinges 59 so that they will bear directly down on the base, when set up, and thus relieve the hinges from excessive strain. The opposite section D¹ is hinged at its lower edge as at 65 to a member 66, both the legs 67 and the outer members 68, 69 and 70 being on the outer side of the hinges, however, so that when the crate is folded down there will be a sufficient space or pocket between the members 64, 60, 62, 61, and 67—70, to contain the two detached end sections. The end sections consist of frames each having vertical legs 71 connected by cross members 72, 73 and 74. The lower ends of the members 71 lock behind cross strips 75 at the ends of the bottom section, while the outer ends of the members 72, 74 project to engage against the edges of the sections C¹ and D¹, while the vertical members 71 snugly engage the inner faces of the members 64, 67, to brace the crate. The cover B¹ is somewhat similar to the cover B and is locked by a similar securing latch 41. As this crate is too high, however, to permit the cover to be dropped back (as in Fig. 10) without straining the connecting hinges, the cover is also made detachable by hinges of the type shown in Fig. 12. This hinge consists of a loop member 76, on the slat 70, and a hook 77 on the cover. This hook is so formed that it may be released from the loop when the cover has been swung wide open, but is securely fastened when the crate is closed. The ends of the cover B¹ are further provided with angular fingers 78 which are arranged to engage the upper ends of the end sections to lock them in place. It will thus be seen that when the latch 41 is released and the cover is opened up, the end sections may be lifted out and enclosed within the other sections when the cover is re-attached and the crate is collapsed. Latch members 79—80, arranged on the side sections, are provided to lock the crate closed in its collapsed condition.

In the modification shown in Fig. 13 the base A² has floor boards 81 connected by cross slats 82 on the under side, and an edge piece 83 at one edge. The side sections C² and D², are hinged in substantially the same manner as in Fig. 11. They consist, however, of double vertical members 84 and 85, connected by cross members 86, so that a deeper space will be left between the opposite members 86 when the crate is collapsed. This is required especially in crates

where the end sections are restored face to face and not edge to edge, or in the event that unusually thick or heavy end sections are used.

The construction illustrated in Figs. 14 and 15 is substantially similar to the crate as shown in Fig. 11, the sections A³, B³, C³, D³, and E³, being somewhat like the corresponding sections A¹, A², etc., except for the following changes: The end section members 71 lock between the members 72, 74 and 64, as above, but are secured by the cover through a strip 87, which is secured to the upper members 88 of the cover, such members being slightly longer than the corresponding members of the cover B¹, so that the ends of the cover will have a fuller bearing on the end sections. Instead of the diagonal brace 73 each end section E³ is also provided with a third horizontal or intermediate slat 89 which is arranged to lock the end section to the crate when the cover is open; and thus not only strengthen the crate but also holds it together when the cover is open and the crate is being filled. The lock or latch used is somewhat similar to the previously described latch 41 and consists of a holder 90, having a slot 91 and a spring actuated bolt 92, the slat 89 having a pocket 93 to receive the holder 90 and a nail or other suitable pin 94 to be received in the slot 91 and detachably retained by the bolt 92. The latch 79 is also of a similar construction and locks the crate closed by detachably receiving a bail of the member 80 in its slot.

In the modification shown in Figs. 16, 17, 18 and 19, the end sections E⁴, F⁴ are practically identical to the end sections E¹, F¹, but the hinging and construction of the other sections A⁴, B⁴, C⁴, and D⁴ is modified. Thus, the base or bottom section consists of outer bars 95, and inner bars 96 to which are secured the floor boards 97. The side sections C⁴ and D⁴ consist of vertical rails 98 connected by horizontal slats 99. The lower ends of the rails or legs 98 are pivotally secured, by rivets 100, between and to the members 95—96, but are long enough so that when the crate is set up they will bear directly on the floor and thus relieve the rivets 100 from excessive strain. Suitable plates 101 may be secured on the pivoted members, to act as bearings and prevent the rivets from splitting the slats or wearing through. The lower ends of the end section legs 71 are inserted in between the bars 95 and 96, while their upper ends are arranged to be received and locked between corresponding rails 102 and 103 of the cover section B⁴. The cover is completed by slats 104 which are secured to all the members 102, 103, although one of them 105 (Fig. 16) may be shorter and connect only the inner rails 103 so as not to interfere with the adjacent side section members 98 when the

crate is collapsed, as in Fig. 17. (It is obvious that the floor boards 97 cannot extend to the bars 95 as they would interfere with the folding). The cover B⁴ is riveted, as at 106, to the section D⁴, but is detachably pivoted or hinged to the section C⁴, by suitable means such as bolts 107, so that the cover may be conveniently opened, and so that the sections E⁴, F⁴ may be detached, for collapsing purposes.

In the crate shown in Figs. 20 and 21, the sections A⁵, B⁵, C⁵ and D⁵ are quite like the corresponding sections shown in Fig. 16, except that the rails 95 and 102 are omitted. The end section E⁵ consists of a simple bar 108, which is permanently riveted, as at 109, to the side section leg 110, while its other end is detachably secured as at 111 to the opposite side section. A hole 112 is also provided in the upright 110, and is spaced from 109 so that the bolt 111 can secure the bar 108 to the leg when the crate is knocked down. This eliminates the necessity of a complete frame for each end section, which is not necessary for instance when single pieces of furniture or machinery are being crated. Fig. 21 illustrates a preferred method of strengthening the joints of the crate, and shows the leg 98 as having hanger plates 113 which journal the rivet 100 at their lower ends, while the upper ends are secured to the leg, so that the pull downward will be distributed to higher points. The base rail 96 is provided with plates 101 and 114, the latter of which is bent and secured under the rail so as to greatly strengthen it.

The crate shown in Fig. 22 includes a shallow base A⁶ to which is pivoted, at each end, the side sections C⁶ and D⁶, a rail 115 (similar to 95) being employed to form a receiving slot for the detachable end section F⁶. The cover section B⁶ consists of a pair of outer rails 116 connected by slats 117. The end section F⁶ includes a pair of diagonal section braces 118, to engage outwardly against the members 115, 116, and a pair of transverse or horizontal slats 119 (similar to 72—74) to bear inwardly against the vertical rails 120 of the side sections. This type of end sections is found very desirable under certain circumstances as swelling and expansion of the diagonal members 118, by reason of moisture, will not tend to bind or tighten the section as much, for instance, as with the use of both vertical and horizontal slats.

The crate shown in Figs. 23 and 24 has many features and characteristics which are also common to previously described constructions, although some differences are present and will now be set forth. Although the elevation may be considered either as a side or end view depending upon the proportionate dimensions and method of construction employed, it will here be con-

sidered as an end view, for convenience of description. This crate is particularly designed as a poultry coop, and includes a shallow base A⁷, a similar but inverted cover section B⁷, side sections C⁷ and D⁷, which pivotally connect the upper and lower sections; and detachable end sections F⁷ (and E⁷ not visible). The base and cover sections are pivoted to the inner sides of the rails 121 of the side sections, the joint between B⁷ and D⁷ being arranged to be broken, as at 122, for reasons heretofore set forth. The sections F⁷ (and E⁷) consist of vertical slats 123 and horizontal slats 124, which interlock with the sections A⁷, B⁷, C⁷, and D⁷, the vertical slats 123 bearing inwardly against the horizontal members 125 and 126, while the horizontal slats 124 bear outwardly against the members 121.

It is understood that various and suitable modifications, other than those herein set forth, may be made in the crate, or in its structural details and general design, provided, however, that such modifications come within the spirit and scope of the appended claims.

Having now therefore fully shown and described my invention, what I claim to be new and desire to protect by Letters Patent is:

1. A collapsible crate comprising a base, a pair of side sections adapted to fold one down upon and the other away from the base, means for hingedly securing the side sections to the base, one of the hinge centers being offset vertically from the other so that when the side sections are collapsed to a horizontal position they will lie in different planes, a cover arranged to swing from the upper edge of one of said sections and to be detachably secured to the upper end of the other section, and end sections arranged to close the ends of the crate and brace the crate in its set up position.

2. A collapsible crate comprising a base, a cover and side sections hingedly connected to each other at adjoining edges, the hinges at one side of the crate being offset vertically with respect to the hinges at the other side, and end sections, arranged to interlock with the cover, to close the ends of the crate, said side sections being foldable one down upon and the other away from the base when the crate is to be collapsed.

3. A crate comprising a base, side sections hingedly secured thereto and adapted to fold one down upon and the other away from the base, a cover hingedly secured to one of said sections and detachably secured to the other section, and end sections for closing the ends of the crate, said end sections being arranged to interlock with the cover when the latter is closed down whereby they will be locked into operative or set up position by the cover.

4. A collapsible crate comprising a base,

a cover and side and end sections, said side sections being hingedly secured to the base whereby they may be swung one over and one away from the base when the crate is to be collapsed, and means independent of the hinge connections, whereby vertical pressure on the side sections will be conveyed directly to the base.

5. A collapsible crate consisting of a base,
10 a pair of side sections hingedly secured there-
to for swinging movement in the same direc-
tion, a cover hingedly connected at one edge
to one of the side sections and detachably
connected at its opposite edge to the other
15 side section, detachable end sections adapted
to be inserted at the ends of the crate, and
means associated with and affected by a clos-
ing movement of the cover for locking said
end sections in place.
- 20 6. A collapsible crate comprising a base, a
cover, and side sections adapted to be folded

one down upon and the other away from the base, said side sections being secured by upper and lower hinges to said cover and base, the hinges of one side section being higher 25 than the hinges of the opposite side section, so that when the crate is collapsed the said base, cover and side sections will fold flatly against each other.

7. A collapsible crate comprising a base, 30 a cover and side sections hingedly secured together at their four adjoining edges, de-
tachable end sections, and means associated
with said base, cover, and side sections, for
receiving and locking said end sections in 35 place, the hinge connection between the
cover and one of said side sections including
means for releasing the cover whereby it
may be swung open from the opposite side
section.

In testimony whereof I affix my signature.
CORNELL FLAGSTAD.
